UNITED STATES PATENT OFFICE.

EMORY CROUSE, OF WICHITA, KANSAS.

LIQUID-TURBIDITY INDICATOR.

Application filed November 27, 1922. Serial No. 603,468.

To all whom it may concern:

Be it known that I, EMORY CROUSE, a citizen of the United States, residing at Wichita, Kansas, in the county of Sedgwick 5 and State of Kansas, have invented certain new and useful Improvements in Liquid-Turbidity Indicators; and I do declare the following to be a full, clear, and exact description of the invention, such as will enable others skilled in the art to which it 10 pertains to make and use the same, reference being had to the accompanying drawings, and to the characters of reference marked thereon, which form a part of this specification.

This invention relates to an improvement in the construction of devices used for the dispensing of gasoline and lubricating oil.

It is customary at the present time to dis-

20 pense liquid fuel by means of an apparatus which requires that the liquid be first elevated into a transparent graduated measuring bowl which is usually constructed of glass. The fuel is then transferred through 25 a hose, by the action of gravity, to the fuel tank of the consumer. A dispensing apparatus of the type referred to is shown and described in my co-pending application, Serial Number 538,171, filed February 21, 30 35 to which application reference may be had for the description of the apparatus as a whole. As my present invention relates only to the measuring bowl and parts directly associated therewith, I shall limit the 35 present description and drawings, as well as the claims, to my specific improvement and such parts as necessarily co-operate with it.

It has been found from actual observation 40 and experience that when a transparent glass bowl is filled with gasoline, even of the clearest and purest available, it will appear to be more or less turbid, with the result that it is very difficult for the purchaser to distinguish between a good and an inferior grade of gasoline by its appearance only.

It is the object of this invention to provide means whereby the apparent turbidity of the best grade of gasoline will be eliminated and at the same time the real turbidity of poorer grades will still be apparent. This will then enable the purchaser to form a correct estimate of the quality of the fuel he is purchasing.

55 It is a further object of this invention to improve the appearance of the dispensing

apparatus and to reduce to a minimum the disturbance of the liquid surface in order that more accurate readings may be made.

I accomplish the above results by the simple expedient of providing an opaque cylinder within the transparent glass bowl and spacing the same a short distance from the inner surface of the bowl. The outer surface of the inside cylinder is preferably of such a nature that it will reflect the light. The result of this arrangement is that the liquid between the glass bowl and the reflecting surface will appear clear, unless it is actually turbid and besides this, the arrangement accentuates the level line of the liquid so that it is more clearly visible, thus enabling the operator to stop the flow with greater exactness with respect to the graduations.

In order to more clearly describe my invention, I shall have reference to the accompanying drawing, in which—

Fig. 1 is a perspective view of the upper portion of a liquid dispensing device and shows the transparent graduated measuring bowl.

Fig. 2 is a perspective view of the graduated measuring bowl with parts thereof broken away so as to show the inner cylinder.

Fig. 3 is a transverse section taken on line 3—3, Fig. 2.

Fig. 4 is a view showing a central vertical section of a glass bowl with a reflecting cylinder in place therein, this view being for the purpose of showing a slight modification in the manner of holding the cylinder properly spaced from the cylinder walls.

Fig. 5 is a section taken on line 5—5, Fig. 4.

Fig. 6 is a side elevation of the inside cylinder.

Fig. 7 is a section taken on line 7—7, Fig. 6, and shows the manner in which the edges are joined; and

Fig. 8 is a vertical section of a modification in which the reflecting cylinder is employed in a device intended to be used in devices for vending lubricating oil.

The same reference numbers will be used to designate the same parts throughout the several views.

Fig. 1 represents the upper portion of a gasoline dispensing apparatus having a graduated glass cylinder 1 which serves to measure the gasoline. This cylinder rests

upon a cast-iron base 2 and is provided on top with a cap 3. The mechanism by which the gasoline is raised to the elevated tank 1 has been clearly described in my co-pending 5 application above referred to, and, as it forms no part of the application, it will not be described here. Within the glass cylinder 1 I place a cylinder 4 which is preferably made of aluminum, having the outer 10 side polished so as to be highly reflective. It is not necessary, however, to make the cylinder of aluminum, as any metal or other material that can be so prepared that it will have a reflecting surface, will serve the purpose 15 and I may therefore use sheet cooper, which has one side nickel-plated and polished common tin or porcelain.

The cylinder 4 is preferably formed from a thin sheet bent into circular form, one 20 edge being provided with two or more teeth 5 which engage one side of the opposing edge in the manner shown in Figs. 6 and 7. The outside of the cylinder 4 is smaller than the inside of the glass cylinder 1 and is concentric therewith. This leaves an annular 25 space between the two. In order to properly center the reflecting cylinder within the glass cylinder 1 I provide near each end thereof a plurality of screws 6 which project through the sides of the inside cylinder and engage the inner surface of the glass bowl. The screws 6 may be adjusted so as to center the inside cylinder in the bowl. It is evident that three screws spaced 30 120 degrees apart will be sufficient, but a greater number may be used, and in Fig. 3 I have shown four spaced 90 degrees apart. Instead of screws 6, I may provide each end of the cylinder with tongues 7 which are 35 cut from the metal and bent outwardly so as to engage the inner surface of the bowl 1 (Figs. 4, 5, 6 and 7). When the reflecting cylinder is kept centered by means of the integral fingers 7, all danger of breakage 40 of the glass bowl, due to the unequal expansion of the metal and the glass, is avoided, as the fingers 7 will yield to comparatively slight pressure.

Although the arrangement shown in Figs. 50 1, 2 and 3 is primarily designed to be used in connection with the dispensing of gasoline, it is evident that a similar arrangement can be used for dispensing lubricating oil. In the latter case, however, the parts can be 55 made smaller, as smaller quantities are usually sold.

It is oftentimes desirable to have means incorporated in a pipe, used for dispensing lubricating oil, which will enable one to see 60 the oil as it flows through the pipe from the reservoir or tank to the measure. In Fig. 8 I have shown my present invention em-

bodied in a device that can be incorporated in any pipe and which will make the liquid visible as it flows. I take a glass tube 8, 65 which may be any desired size and length, but which we will consider for the purpose of this description to be of about two (2) inches outside diameter. Clamped against the ends thereof by means of bolts 9 are caps 10 70 which are spaced from the ends of the tube by rubber washers 11, each cap being provided with a threaded opening 12 to which pipes may be attached. Within pipe 8 and spaced from the inner surface thereof is a reflecting cylinder 13 which is similar 75 in construction and function to the cylinder 4 described above, and differs therefrom mainly in having the lower end closed by a conical or flat member 14 which may have 80 a small hole therein for the purpose of permitting a limited amount of oil to flow through the tube. It is evident that if the assembly of parts shown in Fig. 8 is connected in a line of pipe through which oil 85 is forced to flow, that the greater portion of the oil will flow through the annular space between the inner surface of the pipe 8 and the reflecting outer surface of the metal cylinder 13 in the manner indicated 90 by the arrows. The light which passes through the oil and is reflected from the cylinder 13 enables the buyer to form a better opinion of the quality of the oil than he could form by looking at it when drawn into 95 a vessel.

From the above it is apparent that I have invented an improved liquid dispensing and clarifying apparatus that enables the purchaser to form a better judgment of the 100 quality of the fuel dispensed and which also adds greatly to the appearance of the apparatus.

Having now described my invention, what I claim is:

1. A device for dispensing gasoline and for indicating turbidity, comprising, in combination, a transparent container having a reflecting member located therein, spaced a short distance from the inside thereof and arranged in parallel relation therewith.

2. A device for dispensing gasoline in measured quantities and for indicating the turbidity thereof, comprising in combination, a transparent graduated measuring bowl which permits the position of the upper level of the gasoline to be observed, and a reflecting member located within the container in substantial parallel relation with the wall thereof, the reflecting surface being spaced a short distance from the inner surface of the container.

In testimony whereof I affix my signature.
EMORY CROUSE.
